(No Model.)

H. C. BURKHEAD.

COUPLING FOR RAILROAD RAILS.

No. 331,612.

Patented Dec. 1, 1885.

UNITED STATES PATENT OFFICE.

HENRY CLAY BURKHEAD, OF HARDIN SPRINGS, KENTUCKY.

COUPLING FOR RAILROAD-RAILS.

SPECIFICATION forming part of Letters Patent No. 331,612, dated December 1, 1885.

Application filed September 17, 1885. Serial No. 177,372. (No model.)

To all whom it may concern:

Be it known that I, HENRY C. BURKHEAD, a citizen of the United States of America, residing at Hardin Springs, in the county of 5 Hardin and State of Kentucky, have invented certain new and useful Improvements in Couplings for Railroad-Rails; and I do hereby declare the following to be a full, clear, and exact 10 description of the invention, such as will enable others skilled in the art to which it appertains to make and use the same, reference being had to the accompanying drawings, and to letters or figures of reference marked thereon, which form a part of this specification.

15 My invention relates to certain new and useful improvements in couplings for railroad-rails; and it consists in combining, with the adjacent ends of the rails, the flanges of which are provided with notches, a plate having upwardly-projecting portions which enter said notches, the ends of the rails and said plate being held upon each other by a covering-plate, as will be hereinafter fully set forth, and specifically pointed out in the claim.

20 In the accompanying drawings, which illustrate my invention, Figure 1 is a perspective view of my improvement, showing the same applied to the ends of a railroad-rail. Fig. 2 is a vertical sectional view, and Fig. 3 is a 25 perspective view showing the parts separated from each other.

A A represent the adjacent ends of the rail, the flanges of which are provided with notches a a, into which will lie the upwardly-projecting portions a' of the plate A'.

30 B represents a covering-plate, the edges of which are turned upwardly and inwardly, so as to embrace the flanges of the rail, and said

covering-plate is provided with recesses b, into which the spikes that are driven in the ties will enter, so as to prevent said plates moving longitudinally upon the rails.

To secure the adjacent ends of the rails A A to each other, the covering-plate B is first slipped upon one end of one of the rails, and the plate A' is then placed under the rail and above the cross-ties, so that the upwardly-projecting portions a' will enter the recesses a a in the flanges of the rails. The covering-plate B is then moved over the joint and the plate A', thus holding the parts securely together.

35 It will be seen by the construction herein-before described that fish-plates are entirely dispensed with, and that the ends of the rails are provided on their under sides with a bearing-surface, which will keep said rails even, besides holding them firmly together.

I claim—

40 In a joint for railroad-rails, the rails provided with notches a a, a plate with upwardly-projecting portions, which enter said notches, and a covering-plate, B, provided with notches b, with which engage spikes, so as to prevent longitudinal movement thereof upon the rails, 45 substantially as shown, and for the purpose set forth.

45 In testimony whereof I affix my signature in presence of two witnesses.

his
HENRY CLAY X BURKHEAD.
mark.

Witnesses:

J. R. MEECE,
G. T. CONDER.
